UNITED STATES PATENT OFFICE.

JAMES HARTLEY, OF PHILADELPHIA, PENNSYLVANIA.

FIRE ALARM AND EXTINGUISHER.

1,084,208.

Specification of Letters Patent.

Patented Jan. 13, 1914.

Application filed September 24, 1912. Serial No. 722,057.

To all whom it may concern:

Be it known that I, JAMES HARTLEY, a citizen of the United States, residing at Philadelphia, in the county of Philadelphia and State of Pennsylvania, have invented new and useful Improvements in Fire Alarms and Extinguishers, of which the following is a specification.

My invention relates to a new and useful improvement in fire alarms and extinguishers, and has for its object to provide an exceedingly simple and effective device which may be readily set to come into action at a predetermined temperature, and when this temperature is reached, the nozzle will be opened and the liquid flowing therefrom be thrown by an automatic spray wheel in such manner as to reach every part of the room in which the device is located.

A further object of my invention is to provide for the re-setting of the device after it has been brought into action by simply replacing a small inexpensive disk on the face of the setting nut.

A still further object of my invention is to provide for the sending of an alarm to a suitable station or annunciator so that the location of the device which has been set off will be at once determined.

With these ends in view, this invention consists in the details of construction and combination of elements hereinafter set forth and then specifically designated by the claim.

In order that those skilled in the art to which this invention appertains may understand how to make and use the same, I will describe its construction in detail, referring by numeral to the accompanying drawing forming a part of this application, in which—

Figure 1, is a side elevation of my improved fire extinguisher showing it set. Fig. 2, is a central vertical section of the device showing the movable parts in the position they assume after the device has been set off. Fig. 3, is a plan view. Fig. 4, is a plan view of the spray wheel, and Fig. 5, is a face view of the bridge plate.

In carrying out my invention as here embodied Fig. 1 represents, what I term, the head, which has cast therewith a shank 2, said shank being suitably threaded for attachment to the pipe line through which the water or other extinguishing liquid flows and with this head is formed a frame 3 hav-

ing a boss 4 formed on its lower end and an extension 5 of said boss between the side bars thereof. In these bosses are formed bearings in which the supporting rod 6 is fitted to slide vertically. The upper end of this rod has a socket bearing for the reception of the spindle 7. 8 is an automatic spray wheel attached to or formed with the spindle 7 and carrying a valve 9 which latter is adapted to close upon the valve seat 10. This valve and valve seat being here shown as conical but it is to be understood that this valve and seat may be of any shape or design best adapted to serve the purpose for which the device is intended.

The spray wheel consists of a rim 11, a central section 12 and blades 13 which latter may be formed with the central section and these blades are set at an angle after the manner of propeller blades as clearly shown in Fig. 2, for the purpose hereinafter set forth. The rod 6 is shouldered as indicated at 14 and a spring 15 is interposed between said shoulder and a shoulder formed in the boss extension in such manner as to tend to force the rod downward from the position shown in Fig. 1, to the position shown in Fig. 2.

The boss 4 is threaded to receive the setting nut 25 which latter has a hole 16 in the bottom thereof through which the reduced portion 17 of the supporting rod 6 is adapted to pass. This nut has formed therewith the lugs 18 the lower ends of which are inturned to support the bridge plate 19 the latter having notches in its ends to engage the lugs 18 to prevent the accidental displacement of the bridge plate when the device is set. This bridge plate also has a hole in its center for the passing of the reduced portion of the supporting rod.

20 represents a disk which may be made of material, fusible at a relatively low temperature and adapted to be united to the lower face of the bridge plate over the central hole in order that the reduced portion 17 of the supporting rod may rest thereon, or this disk may be made of material such as brass or iron and secured to the under side of the bridge plate with a solder whose fusible point is low.

21 represents a contact strip which is secured to but insulated from the setting nut and projects into the path of the reduced

- portion 17 of the supporting rod so that when the latter is forced downward by the spring 15 it will come in contact with said contact strip closing the electric circuit in 5 which is included the wire 22 attached to the frame by the screw 23, the frame, the supporting rod journaled in said frame, the contact strip 21 and the wire 24. The wires 22 and 24 lead to a central station and are 10 connected with an annunciator so that when the circuit is closed as just described, an alarm will be given at the central station and the location of the extinguisher which has been set off, indicated. 15 The giving of an alarm and the indicating of the location of the extinguisher brought into action is of great importance since it often saves great damage from flooding.
- From the foregoing description, the operation of my invention is as follows: In 20 practice the extinguishers are attached to branch pipes leading from the main line which supplies the extinguishing fluid usually water, and are located at different 25 points where fire is likely to occur and each extinguisher is set by the valve 9 being forced against its seat 10 by means of the setting nut 25 which carries by the bridge piece 19 and the disk 20, the latter being jammed 30 against the supporting rod with sufficient force to firmly hold the valve upon its seat and prevent leakage. Now should the temperature rise to a dangerous point predetermined by the fusing point of the disk 35 or the solder by which it is attached to the bridge plate, the disk will be displaced freeing the supporting rod which will be forced downward by the spring 15 and the pressure upon the valve, bringing the parts to 40 the position shown in Fig. 2, and permitting the water to flow from the supply pipe. As this water flows from the supply pipe, it will be spread by the valve 9 and will come in contact with the blades 13 of the 45 spray wheel causing said wheel to revolve and this revolving of the wheel will throw

the water to a relatively great distance in the form of spray, thereby preventing the fire from starting or if started extinguishing the same.

As before described as soon as the extinguisher is set in operation an alarm will be turned in, indicating the location of the trouble in order that immediate attention may be given thereto.

When the extinguisher has been set off and accomplished its work, it is readily re-set by removing the bridge plate re-soldering a disk 20 thereto replacing the plate and again jamming the valve against its seat 60 and putting the device in condition for further use. This is of great value in fire extinguishers of this class since it does not require the disturbing of the extinguisher to re-set the same and can be accomplished 65 quickly and at imperceptible cost.

Of course I do not wish to be limited to the exact details of construction here shown and described as various forms of designs of spray wheels may be used without departing from the limits of the appended 70 claim and other details of the device as here shown may be altered within the limits of said claim.

Having thus fully described my invention, what I claim as new and useful, is—

A fire extinguisher consisting of a head having a shank, a valve seat formed in said head, a valve for closing said seat, an automatic spray wheel carrying the valve, a supporting rod in which the wheel is journaled, a frame in which the rod is journaled, a setting nut adapted to be screwed upon the frame, and a fusible disk carried by the setting nut for supporting said rod as specified. 80

In testimony whereof, I have hereunto affixed my signature in the presence of two subscribing witnesses.

JAMES HARTLEY.
